H. H. PACKER.

Ratchet Drill.

No. 20,728.

Patented June 29, 1858.

UNITED STATES PATENT OFFICE.

HENRY H. PACKER, OF BOSTON, MASSACHUSETTS.

HAND-DRILL.

Specification forming part of Letters Patent No. 20,728, dated June 29, 1858; Reissued January 2, 1868, No. 2,140.

To all whom it may concern.

Be it known that I, HENRY H. PACKER, of Boston, in the county of Suffolk and State of Massachusetts, have invented a new and useful hand ratchet-drill machine for the purpose of drilling or boring holes in metallic or other substances in the process of constructing and erecting machinery and other mechanical purposes where it is not convenient to use the power-drill machine; and I do hereby declare that the following is a full, clear, and exact description of the construction and operation of the same, reference being had to the accompanying drawings, making a part of this specification.

The nature of my invention consists in certain improvements in ratchet hand drills as hereinafter fully described.

To enable those skilled in the art to make and use my invention I will proceed to describe its construction and operation, referring by letter to the accompanying drawings, wherein—

Figure 1, represents an elevation of my improved drill; Fig. 2, a vertical section through the center, and Fig. 3, a horizontal section on the line x, x , Fig. 1.

Similar letters denoting the same parts in the different views.

C, represents the screw barrel the upper end of which is bored out and "taped," to accommodate the screw, B, the lower end being so constructed as to have formed therein a socket for the reception of a drill (see Fig. 2) represented at, d. The head of the screw, B, is conical on top as seen at A, forming a pivot and has projecting from its perimeters downward a shell, A', which (when the screw, B, is at its lowest point in the barrel, C,) entirely surrounds said barrel, its whole length.

C, is a ratchet wheel which is keyed into the lower end of the barrel or drill stock, C, and rotates in an eye on slot formed in the spindle stock, b, for its reception; said ratchet wheel is caused to revolve—carrying with it the barrel, C, screw, B, and shell, A',

and any tool which may be secured in the shank at, d, at every half stroke, or, "every other," vibration of the spindle stock, b, by means of the pawl, g, working on a pivot, i, and kept in gear with said wheel (at the proper times) by a special spring, e. The frame or stock, b, is furnished with a suitable handle, f, on the top of the stock, b, and surrounding the band, A, is a collar, a, from which extends upward a shell, m, surrounding the shell A', the greater part of its length.

The operation of my improved drill is nearly similar to those already in use and requires but little explanation, the whole mechanism is caused to partially rotate at every forward stroke or vibration of the handle, f, by means as already described, while at every backward stroke the pawl, g, rides over the ratchet wheel, c, leaving the mechanism stationary; when it is desired to feed the drill the screw, B, is turned by a simple key or lever fitting a hole in its head, A.

It will be observed then by virtue of the peculiar construction of the drill with shells A' and, m, that the screw barrel, C, with its internal screw thread, and the male screw B, are effectually protected from all dust or other injurious matter; which is a great desideratum; these portions of the machine being those which first give away generally in consequence of the dust which gets in the threads of these screws grinding them away and thus rendering them inoperative.

Having described the construction and operation of my improvement what I claim therein as new and desire to secure by Letters Patent is:

The combination of the cylindrical shells A' and, m, with the feed screw and screw barrel; substantially as and for the purpose specified.

HENRY H. PACKER.
